UNITED STATES PATENT OFFICE.

HARRIET E. FENNER, OF DES MOINES, IOWA.

MAIL-BOX FLAG.

Application filed August 7, 1924. Serial No. 730,750.

To all whom it may concern:

Be it known that I, HARRIET E. FENNER, a citizen of the United States, and a resident of Des Moines, in the county of Polk and State of Iowa, have invented a certain new and useful Mail-Box Flag, of which the following is a specification.

The object of my invention is to provide a mail box flag structure of simple, inexpensive and durable construction adapted for use as an indicating device in districts where there is rural delivery of mail.

The further object of my invention is to provide a flag which can be permanently, rigidly and properly mounted on the mail box, comprising a pivoted or hinged flag portion having a second flag hinged thereto for the purposes hereinafter more fully set forth.

With these and other objects in view, my invention consists in the construction, arrangement and combination of the various parts of my mail box flag, whereby the objects contemplated are attained, as herein-after more fully set forth, pointed out in my claims, and illustrated in the accompanying drawings, in which:

Figure 1 shows a perspective view of a mail box equipped with an indicating flag embodying my invention.

Figure 2 is a sectional view of a portion of the mail box, the flag being indicated in full lines in its folded position.

Figure 3 is a detail view showing the hinge structure of the flag in side elevation; and

Figure 4 is a detailed front elevation of the hinge structure.

In the accompanying drawings, I have used the reference numeral 10 to indicate generally a post on which is mounted a mail box 11, which may be of any suitable desired construction.

My improved flag comprises an upright bar 12 secured to the box 11 by means of screw bolts or the like 13, the bar 12 being secured in an upright position on the side of the box.

The bar 12 may have at its lower end a flange 14 to extend under the box to insure the more rigid mounting of the bar.

Connected with the upper end of the bar 12 by means of a hinge A is the flag staff 15.

It should perhaps be mentioned in this connection that the bar 12, the flag staff

and the flags and the other parts so far as possible are made of galvanized material or other material which will not corrode on account of exposure to the weather.

The bar 12 and the staff 15 are connected together by a hinge A comprising the journal members 16 and the pintle 17. The bar 12 and staff 15 are provided adjacent to each other with holes 18 and 19.

A coil spring 20 is arranged adjacent to one of the pintles and has its ends 21 and 22 inserted into the holes 18 and 19, so that the resiliency of the spring tends to press the ends together.

Thus it will be seen that when the staff is upright, the spring will hold it in upright position, whereas when the staff is swung laterally outwardly or downwardly, the ends of the spring will first be sprung apart on account of the fact that the pintle 17 is not aligned with the holes 18 and 19, and as the staff swings farther down the upper spring will pass center, and when the staff drops to its position shown by dotted lines in Figure 3, the spring will tend to hold the shaft 80 in its lowered position.

The staff 15 has at its outer or upper end a flag 23, to be colored red as at 24 on the side toward the highway.

At the upper end of the flag 23 is a short extension 25 to which is hinged a short staff 26 by a hinge and spring similar to the hinge A and spring 20.

On the staff 26 is another flag 27 which is colored orange on the side which can be seen from the residence of the box owner.

The flags thus constructed can be used for indicating a series of facts.

The hinges are arranged so that the staff 15 folds toward the outside and the staff 26 95 folds toward the inside with relation to the box.

When the flag is lowered, no signal is intended at all. When the flag 23 is raised and the flag 27 is lowered, the condition of the flags indicates to the mailman that the household has placed mail in the box for taking up and forwarding.

When the mailman drives past, he knows that he need not stop if the flags are down, but knows that he is to stop if the flag 23 is up. When he puts mail in the box, he raises the flag 27, which indicates to the household that a delivery has been made.

When the flags are down as shown in Fig.

ure 2, the colored side of the flag 23 is next to the box and thus protected from the weather.

This flag is of sturdy construction, so that it will not readily wear out or become loose. It affords a convenient and easy means for indicating the proper facts to the mail carrier and the householder.

I claim as my invention:

- 10 The combination of a mail box with a flag staff hingedly supported thereon to

stand in upright position or to swing down to position alongside the mail box, a flag at the outer end of said staff, a second flag staff hingedly connected beyond the first flag to the staff thereof, a flag on the second staff, the hinges being arranged to fold in opposite directions and to permit the flags to be arranged one above the other or to be folded to positions side by side.

Des Moines, Iowa, July 25, 1924.

HARRIET E. FENNER.
